UNITED STATES PATENT OFFICE.

JAMES E. GUNTER, OF BALTIMORE, MARYLAND, ASSIGNOR TO THE JAMES E. GUNTER CORPORATION, A CORPORATION OF MARYLAND.

CONTAINER.

Application filed April 1, 1926. Serial No. 98,996.

My invention relates to new and useful improvements in closures for containers and more particularly to one in which the cap retaining means may be readily removed without destroying the further usefulness of the container.

An object of the invention is to provide a sealed container which may be economically manufactured; and which can be easily and readily opened without the use of any tool and a cap which, after the container is opened, may be satisfactorily used for closing the container while the contents are being used.

Another object of my invention is to make a container of the above type in which the cap has a friction seal with the container.

Another object of my invention is to make such a container in which the retaining ring may be hollow and may be made of a plurality of turns of a spiral, such as a spiral spring.

Another object of my invention is to provide such a container with pointed projections to hold the retaining ring up toward the mouth or opening of the container, and which tend to push the projecting handle of the retaining ring from the top of its surface, and down between such projections.

Another object of my invention is to make a retaining ring the handle of which has a smaller cross sectional area projecting from between the container and cap than the ring has between the container and cap.

Further objects and advantages will be apparent from the following description and the accompanying drawings:

Figure 1 is a partial cross sectional view of the spiral retaining ring between the container and cap.

Figure 2 is a front view with certain parts broken away.

Figure 3 is a cross sectional view on line 3-3 of Figure 1.

Figure 4 is a front view of the container.

Figure 5 is a partial front view of another modification of the retaining ring.

Figure 6 is a cross sectional view of the modification shown in Figure 5, on line 6-6 of Figure 5.

Similar numerals refer to similar parts throughout the several views.

The container body 1 has an outwardly flared mouth 2 and pointed projections 3 aligned around the body of the container adjacent its mouth. These projections are pointed as shown in Figure 6 for a purpose hereinafter to be described. Within the groove formed by these projections and the flared container top is a retaining ring 4 made of a plurality of turns of a spiral, such as a spiral spring. One end of this spiral projects below the projections 3 to form a handle 7 for the removal of the spiral. The other end of the spiral is coiled smaller and screwed into the larger end as shown in Figures 1 and 2. This construction makes the spiral practically a solid ring.

Placed within the container mouth is a cap 5 having walls parallel to the walls of the container mouth and forming with them a friction seal. The outer edge of the cap is bent around the retaining ring as at 6, so that the retaining ring is pushed firmly against the container by the extreme lip of the cap and the retaining ring thereby holds the cap firmly on the container.

In placing the retaining ring around the container body should the projecting portion of the handle 7 chance to rest upon the top of one of the projections 3, the pointedness of these projections as shown in Figure 6 tend to make the ring creep around the container, so that the projecting part of the handle will not be upon the projection but to one side of it.

In Figures 5 and 6 a retaining ring 9 having its handle 10 drawn to a smaller diameter than the ring is shown, otherwise the construction shown in these figures may be made substantially like that shown in the other figures.

The cap in Figures 1, 2 and 4 is removed by pulling upon the handle 7 which untwists the spiral and gradually it may be pulled out. In this modification the extreme lip of the cap is not bent outward by the removal of the ring, but the ring, rather, is distorted in its removal.

In Figures 5 and 6 the cap is removed by pulling outwardly upon the handle 10 which bends the cap lip outwardly and by continually pulling downwardly and outwardly 5 around the container the ring is removed and the lip is bent outwardly, and the cap may be then removed.

The retaining ring may be made of any material or of any cross section, its only requirement being that it hold its form under the stresses to which it is subjected, and that it have sufficient tensile strength to be pulled out. 10

As many changes might be made in the above arrangements and as many variations might be made without departing from the scope of the invention, it is intended that all features herein described or shown in the accompanying drawings, shall be interpreted 15 as illustrative, and that the invention be limited only by the following claims. 20

I claim:

1. In combination, a container, a cap thereon, a retaining ring comprising a plurality of 25 turns of a spiral surrounding the mouth or opening of said container, the edge of the cap forming a bead surrounding said ring laterally to the extent that the inner periphery of the extreme lip of the cap bearing on the 30 ring is greater than the outer periphery of the container within said ring and less than the outer periphery of the ring, said ring having a projecting handle by which to remove said ring.

2. In combination, a container, a cap thereon, a retaining ring comprising a plurality of turns of a spiral surrounding the mouth or opening of said container, the edge of the cap forming a bead surrounding said ring laterally to the extent that the inner periphery of the extreme lip of the cap bearing on the 40 ring is greater than the outer periphery of the container within said ring and less than the outer periphery of the ring, and a portion of said spiral projecting from said bead to form a handle by which to remove said ring. 45

3. In combination, an open end container portion, a cap thereon, said container portion and cap being provided with adjacent surfaces forming a space having a contracted exit, a member disposed in said space of greater width facing said contracted exit than the width of the contracted exit, said member being hollow but firmly resisting lateral compression and shear, a projecting handle on said member of a thickness between said adjacent surfaces not greater than the width of the contracted exit, said member being adapted to be removed through said contracted exit. 50

4. In combination, an open end container portion, a cap thereon, said cap forming with the outer wall of the container portion a space having a contracted exit, a retaining mem- 55

ber surrounding the open end container portion and disposed in said space of a greater width facing said contracted exit than the width of the contracted exit, a projection on the outer wall of the container portion immediately below said member and said member having a handle projecting from said space and to one side of said projection. 70

5. In combination, an open end container portion, a cap thereon, said cap forming with the outer wall of the container portion a space having a contracted exit, a retaining member surrounding the open end container portion and disposed in said space of a greater width facing said contracted exit than the width of the contracted exit, a plurality of projections on the outer wall of said container portion immediately below said member, and said member having a handle projecting from said space and between said projections. 75 80 85

6. A retaining ring for holding a cap on a container, said ring comprising a plurality of turns of a spiral and being adapted to be placed between the wall of the container and the edge of the cap, and by its resistance to compression and shear, to hold the cap on the container, a strand of said spiral projecting from the path of said ring to form a handle by which to remove said ring. 90 95

7. A hollow retaining ring for holding a cap on a container, said ring being adapted to be placed between the wall of the container and the edge of the cap, and by its resistance to compression and shear, to hold the cap on the container, said ring having a projecting handle of a thickness between the container and cap edge not greater than the thickness of the shell of the retaining ring, by which to remove said ring. 100 105

8. In a container, a cap therefor, a groove with a restricted opening formed by the container wall and the edge of the cap, a hollow retaining ring in said groove, which ring, by its resistance to compression and shear, holds the cap on the container, said ring having a projecting handle of a thickness between the container and cap edge not greater than the thickness of the shell of the retaining ring, by which to remove said ring. 110 115

9. A container seam for the end of a container comprising, a container wall, a retaining ring surrounding the container wall near said end, said ring having a projecting handle, means projecting from said wall to hold said ring up toward said end, a cap having an outer down-turned wall partially surrounding said ring and firmly holding it against said container wall, the internal surface of said down-turned wall which partially surrounds the ring not being bulged outwardly where said handle projects, and the cap also having an inner outwardly facing wall engaging peripherally an inwardly facing wall of the container. 120 125 130

10. A container seam for the end of a container comprising, a container wall, a retaining ring surrounding the container wall near said end, said ring having a projecting handle, means projecting from said wall to hold said ring up toward said end, a cap having a down-turned wall partially surrounding said

ring and firmly holding it against said container wall, the internal surface of said down-turned wall which partially surrounds the 10 ring not being bulged outwardly where said handle projects.
